FIRE-ESCAPE DOOR-LATCHING DEVICE

Lawrence B. Webster, Omaha, Nebr., assignor to
Lloyd M. Rathbun, Omaha, Nebr.

Application October 2, 1931. Serial No. 566,433

11 Claims. (Cl. 292—92)

The invention relates to fire-escape door-latching devices, and has for its object to provide a catch and latch particularly adapted to the spiral or direct-slope form of fire-escapes frequently connected with school buildings and the like where large numbers of individuals, especially children, are gathered and a speedy exit in case of fire is imperative.

A further object is to provide such a device which will at all times be dependable, and remain free from all forms of accidental contingency which might prevent an orderly and hasty exit from the room of a burning building where a large number of individuals are gathered together or crowded; such, for instance, as might happen from a possible clogging of exposed portions of the operating mechanism of the lock where accumulated debris from dusty sweepings and the like might become lodged, whereby the crowding obstructions about a tardy opening might, as frequently happens, create a panic occasioning tragic results.

A further object is to provide a door-catching device whereby its assembled mechanism is attached to the opposite jamb-casings of the entrance to which the doors thereof are hinged, and so constructed that it can be operated by downward pressure of a transverse operating bar extending across the upper portion of the doorway, terminating at opposite ends in inwardly extending levers attached thereto and fulcrumed over pivots protruding from the sides of said jamb-casings; the opposite ends of which levers carry a lock-bar maintaining the doors in a closed position.

With these and other objects in view the invention resides in combination and arrangement of parts as herein set forth, shown in the drawing, described and claimed.

In the drawing, Fig. 1 is a broken-away view showing door-operating mechanism at one end of the doorway, the locking-bar and a part of the door frame in section.

Fig. 2 is a broken plan view in section, illustrating door-operating mechanism at both sides of a doorway, said mechanism being illustrated by a section on line 2—2 of Fig. 1.

Fig. 3 is a sectional detail showing one of the toggle-members used for controlling movements of a rock-lever.

Fig. 4 is a perspective view of one of the toggle-members.

Fig. 5 is a perspective view of one of the doors, the groove-member on its upper end, and a lock-bar disposed in the groove.

Fig. 6 is a perspective view of the lock-bar.

Referring now to the drawing, numerals 1 indicate portions of the walls of a building to which a fire-escape of any slideway form may be attached, between said wall-portions 1 being shown an opening or doorway, said doorway being provided with the usual face casings 2 and jamb-casings 3.

The opening leads directly into the fire-escape and is normally closed by a pair of doors 4 which are provided with spring-hinges 5 securing them to the outer edges of the jamb-casings 3.

The doors are shown in a closed position by action of the spring-hinges 5 and may be maintained in closed position by means of a lock-bar 6, the horizontal portion of said bar being engaged within grooves 7 which are formed in the inner portions of the metallic members 8 which overreach the upper ends of said doors and are secured thereto by means of wood-screws 9.

It is obvious that said lock-bar 6 when raised out of the grooves 7 will release the doors 4 and permit the spring hinges to force them open.

The lock-bar 6 is provided at its ends with depending portions 6' which are slidingly mounted in vertical grooves 11 which are formed in the metallic plates 12 which are secured to the jamb-casings 3 of the doorway and disposed flush with said casings.

The lower ends of the depending portions 6' are provided with inwardly projecting studs 10 adapted to operatively engage the forked ends of the pair of rock-levers 13 which are fulcrumed upon shoulder-screws 14 which pivotally sustain them at the sides of the plates 12, the outer ends of said rock-levers being mounted on an operating-bar 15.

In order that the rock-levers 13 may be sustained in a stationary position after moving the operating-bar in either position, spring toggle-members are provided, each consisting of an end-tapered bolt 16 slidingly mounted in a sleeve 17 having a helical spring 18 therein which tends to force the bolt naturally against the side of a rock-lever 13, the tapered end of said bolt engaging in an indentation 19 which is formed in the side of a rock-lever, an upward or downward movement of the operating-bar 15 and rock-levers 13 causing rocking movements of the toggle-members, the latter rocking about a pair of opposed extensions 20 which engage pivotal centers upon opposite sides of openings 21 formed through plates 12 and attached plates 22.

It is obvious that the pressure of said bolts 110

16 is in a direction at right-angles to the faces of the rock-levers while the latter are in positions intermediate the extreme range of their movements, and therefore the toggle-members in 5 their upper or lower positions will resist movements of the rock-levers toward intermediate positions.

From the above it will be seen that a door-latching device is provided which differs from 10 other appliances of this character in the elimination of inconvenient obstructions which a latching mechanism naturally entails whenever any portion thereof is attached to the door. In this, however, a structure is provided whereby individuals may effect a hasty escape by grasping the 15 operating-bar (which crosses the doorway at about normal attitude of their hands) while the applied downward pressure will unfasten the doors, thus permitting the enclosed occupants 20 to swing under the operating-bar, feet foremost, into the descending slideway where, after releasing their grasp, they will slide down to the exit.

The invention having been fully described what I claim as new and useful is:

25 1. In a fire-escape door-latching device for a pair of doors mounted to swing from a doorway, a pair of rock-levers mounted in the sides of the doorway, a lock-bar having end-portions slidably engaging the rock-levers at the outer 30 ends thereof and adapted to engage the doors for maintaining them in closed position, and an operating-bar mounted on the inner ends of the rock-levers adapted to be moved for coincident actuation of said levers to cause disengagement 35 of the lock-bar from said doors.

40 2. In a fire-escape door-latching device for a door mounted to swing from a side of a doorway, a pair of rock-levers mounted in the sides of the doorway, a lock-bar having end-portions mounted 45 on the outer ends of the rock-levers and adapted to engage the door for maintaining it in closed position, and an operating-bar disposed approximately parallel with the lock-bar and mounted on the inner ends of the rock-levers, said operating-bar being movable for moving the rock-levers to cause disengagement of the lock-bar from said door.

45 3. In a fire-escape door-latching device for a pair of spring-controlled doors mounted to swing from a doorway, metallic plates provided with grooves and mounted on the sides of the doorway, a pair of rock-levers mounted on said metallic plates, a lock-bar adapted to engage said doors for maintaining them in closed position and having end-portions engaging in the grooves of said plates and having projections slidably mounted in the outer ends of the rock-levers, an operating-bar mounted on the inner ends of the rock-levers and adapted to be moved for causing disengagement 55 of the lock-bar from the doors, said lock-bar having sliding movements of its end-portions in the grooves of said metallic plates.

60 4. In a fire-escape door-latching device for a spring-controlled door mounted to swing from a doorway, metallic plates mounted on the sides of the doorway and provided with vertical grooves, a pair of rock-levers mounted on said metallic plates, a lock-bar adapted to engage said door for maintaining it in closed position 65 and having end-portions engaging in the grooves of said plates and having projections extending inwardly from said end-portions in engagement with said levers, an operating-bar mounted on the inner ends of the rock-levers adapted 70 to be moved for coincidentally moving the rock-

75 levers to cause disengagement of the lock-bar from said door, said lock-bar having sliding movements of its end-portions in the grooves of said metallic plates.

80 5. In a fire-escape door-latching device for a pair of spring-controlled doors mounted to swing from a passageway, rock-levers provided with recesses and mounted in the sides of the passageway, a lock-bar adapted to engage the doors for maintaining them in closed positions and having end-portions mounted on the outer ends of the rock-levers, an operating-bar mounted on the inner ends of the rock-levers and adapted to be moved for moving the rock-levers to cause 85 disengagement of the lock-bar from said doors, and spring-controlled toggle-members mounted in the sides of the passageway and engaging in the recesses of the rock-levers for maintaining said levers in stationary positions after they have been moved by said operating-bar.

90 6. In a fire-escape door-latching device for a pair of doors arranged to swing from a passageway, a pair of metallic plates mounted in the sides of the passageway and provided with vertical slots, each door being provided with a horizontal retaining-groove opening on its top, a pair of rock-levers provided with recesses and mounted in the metallic plates, a lock-bar in said retaining-grooves for maintaining the doors in closed position and having end-portions disposed in the vertical slots of said plates and having projections engaging said rock-levers, a pair of toggle-members each mounted in a side of the passageway and engaging in a recess of a rock-lever, and an operating-bar disposed approximately parallel with the lock-bar and adapted to be moved for actuating said rock-levers to cause a release of said lock-bar from the retaining 95 grooves of said doors.

100 7. In a fire-escape door-latching device for a pair of doors mounted to permit swinging movements from the walls of a doorway, a lock-bar horizontally disposed across the upper portions of the doors to retain them in closed position, rock-levers fulcrumed on side walls of the doorway movable for raising said bar to release said doors, an operating-bar connecting the inner ends and adapted to be moved for moving said levers, and toggle-members in the sides of said doorway in engagement with said levers to yieldingly retain them in released or locked position.

105 8. In a fire-escape door-latching device for a pair of doors mounted to swing from the sides of a doorway, metallic members mounted upon the upper ends of the doors and provided with grooves, a horizontal lock-bar adapted to engage in said grooves for retaining the doors in closed position and having depending end-portions with projections, metallic plates secured to the sides of the doorway and provided with slots receiving the depending end-portions of said lock-bar, rock-levers fulcrumed on said metallic plates and engaging the projections of said depending end-portions, an operating-bar disposed at right angles to the rock-levers and secured to the inner 110 ends of said levers, and a pair of toggle-members each having a part traversing a metal plate and engaging a rock-lever to retain the same in released or locked position.

115 9. In a fire-escape door-latching device for a pair of doors having grooves opening on their upper ends and mounted to swing in a doorway having walls provided with vertical slots, a horizontal lock-bar in the grooves of said doors having depending end-portions slidably disposed in 120

- the slots of said walls, levers fulcrumed on said walls and connected with the depending end-
portions of the lock-bar, an operating-bar dis-
posed parallel with the lock-bar and connected
5 with said levers and adapted to be moved for
moving the lock-bar from said grooves, and
spring-controlled members yieldingly engaging
said levers to maintain the operating-bar and
lock-bar in stationary positions after they have
10 been moved.
10. In a fire escape door-latching device for
a door hinged to a doorway to normally swing
to open position, a lock-bar for engaging the
door, a pair of rock-levers fulcrumed on the
15 sides of the doorway and connected at their outer
ends with the lock-bar, an operating-bar con-
nected with the inner ends of the rock-levers and
adapted to have a swinging movement in one
direction for coincidentally moving the rock-levers
20 to cause engagement of said lock-bar with the
door while the latter is in closed position and
to be moved in an opposite direction to cause
disengagement of the lock-bar from said door
to permit the latter to move to open position. 80
11. In a fire-escape door-fastening device for
a door hinged to a doorway to permit a swing-
ing movement to closed position and normally
to swing to open position, a lock-bar adapted to
engage the door to maintain it in closed posi-
tion, a pair of rock-levers fulcrumed on the sides
of the doorway and connected at their outer ends
with the lock-bar, an operating-bar connected
with the inner ends of the rock-levers and adapt-
ed to be moved for disengaging the lock-bar from
the door to permit it to swing to open position,
and a detent-member on the doorway co-operat-
ing with said rock-lever tending to maintain the
lock-bar disengaged from said door. 85 90
